UNITED STATES PATENT OFFICE.

JAMES A. JOHNSON, OF DANVILLE, VIRGINIA, ASSIGNOR TO DANVILLE CONDITIONING MACHINE COMPANY, OF DANVILLE, VIRGINIA, A CORPORATION OF VIRGINIA.

YARN-TREATING MECHANISM FOR WINDING MACHINES.

Application filed August 6, 1921. Serial No. 490,253.

To all whom it may concern:

Be it known that I, JAMES A. JOHNSON, a citizen of the United States, residing at Danville, in the county of Pittsylvania and State of Virginia, have invented certain new and useful Improvements in Yarn-Treating Mechanisms for Winding Machines, of which the following is a specification, reference being had to the accompanying drawings.

This invention relates to the conditioning or treating of yarn prior to its being wound upon a cone for use in knitting, and particularly to means for supplying moisture to the yarn or conditioning it, as it is called.

In the ordinary conditioning of yarn, the yarn is wound upon the usual paper cone and then these cones are placed within a conditioning room where they are submitted to the action of moisture, the room being filled with a very fine spray or vapor from suitable spraying devices. This in theory moistens the yarn so that it sets the twist and prevents kinking, but one of the objections to this method of conditioning the yarn is that it is necessary that the outside layers of the yarn on a cone be moistened beyond the proper percentage in order that the inside layers of yarn on the cone shall have the proper percentage, or else the outside layers of yarn will have the proper percentage of moisture and the inside layers will not have the proper percentage of moisture.

The object of the present invention is to do away with this method of conditioning yarn and do away with the conditioning room by the provision of means whereby the yarn is moistened as it is being wound upon the cone, and further to so construct the moistening means that a uniform amount of moisture will be applied to all the yarn so that the inner layers of the yarn after it is wound upon the cone will have just as much moisture and no more than the outer layers. This prevents the mildewing of the outer layers, which mildewing comes from the outer layers having too great an amount of moisture.

A further object is to provide a mechanism of this kind which may be also used for the purpose of dyeing the yarn for the production of a yarn which has a tint as

distinguished from a solid color, as for instance a gray yarn.

A still further object is to provide means whereby the amount of moisture which is distributed to the yarn may be readily controlled.

Another object is to provide a mechanism of this sort in which the yarn passes over a roller which travels through a tank of liquid, this roller being so formed as to carry a film of liquid up with it and into contact with the yarn.

And another object is to provide means whereby this roller may be given a step by step rotation.

Other objects will appear in the course of the following description.

My invention is illustrated in the accompanying drawings, wherein:

Figure 1 is a top plan view of a section of my moistening device showing diagrammatically the spools or quills from which the yarn is being drawn and the paper cones upon which the yarn is being wound;

Figure 2 is an end elevation of my device, showing the means whereby the shaft is given a step by step rotation and the means whereby the water is supplied to the tank;

Figure 3 is a section on the line 3-3 of Figure 1 and illustrating one of the moistening rolls and a portion of the spool or quill from which the yarn is being drawn and one of the receiving cones;

Figure 4 is an elevation of one end of the moistening shaft showing the means whereby it is operated;

Figure 5 is a sectional view through the tank, showing the means for supporting the shaft therein;

Figure 6 is an elevation of one wall of the tank, showing the means for holding the thread or yarn in contact with the moistening roller;

This invention is intended to be applied to an ordinary form of winding machine in use in mills where cotton is prepared for knitting purposes, and inasmuch as this machine is well known and forms no part of my invention, I have merely illustrated the machine diagrammatically. This machine embodies a plurality of spindles, upon which the spools or quills are mounted, these

quills being designated A, and a plurality of spindles upon which the paper cones on which the yarn is received are mounted, these cones being designated B. The cones rotate, it will be understood, at a high speed and the yarn is taken from the quills or spools A over to the cones B and is wound upon these cones, there being a reciprocating guide b associated with each cone through 10 which the yarn passes and by which the thread is guided upon the cone.

The object of my invention is to moisten each thread or yarn between the quill A and the cone B, and to this end I extend 15 longitudinally of the winding machine a tank 10 which is illustrated as of iron but may be made of any suitable material and is of any suitable depth and cross sectional area. This tank is mounted in brackets 11 20 which embrace the tank, the tank being held in place within these brackets by means of set screws 12 or any other suitable means, each bracket being provided with a foot 13 through which a bolt passes to hold it to 25 a suitable support. This tank extends along the entire length of the machine and may be made in several sections if desired.

Extending longitudinally through the tank or through each section of the tank is 30 a shaft 14 which is mounted within suitable bearings within the tank so that the shaft will not sag, and at one end carries means whereby the shaft may be given rotation. Mounted at intervals along this shaft are 35 moistening rollers 15, these rollers being made of brass or any other suitable material, and are preferably tapered for a purpose to be later stated. Preferably these rollers are formed with longitudinally extending 40 recesses upon the outer face, designated 16, these recesses acting like buckets and being ratchet-shaped so that as the roller rotates in the direction of the arrow in Figure 3, the buckets will carry water up from the 45 tank and distribute it against the yarn which passes over the top of the corresponding roller. Preferably these rollers are tapered to more or less conform to the taper of the cones B.

50 The shaft 14 at one end is provided with a ratchet wheel 17, and coacting with this ratchet wheel to give a step by step rotation to the rollers is an arm 18 which is pivoted upon the axial center of the shaft 55 14, this arm being provided with a plurality of openings 19, and pivotally mounted on a pin 20 extending into any one of these openings is a pawl 21, the tooth of which engages the teeth of the ratchet wheel 17.

60 The pawl is weighted at its opposite end so that the tooth is always held in engagement with the teeth on the ratchet wheel.

In the winding machine which has been referred to, there is a stop motion shaft designated C which oscillates through a cer-

tain angular distance, and in order to oscillate the arm 18 I mount upon this shaft C an arm 22, this arm being held to the shaft C by means of a set screw 23 and this arm as it oscillates is adapted to strike a pin 70 24 disposed in one of the apertures 19 and this will act to oscillate the arm 18 and shift the ratchet wheel and the shaft 14 in one direction. Upon the reverse movement of the arm 22, the pawl 21 will ride over the teeth of the ratchet wheel 17 and the pawl will return to its original position. By adjusting the pin 24 in any one of the openings 19, a greater or less movement of the ratchet wheel may be secured. 75 80

For the purpose of keeping the tank 10 constantly filled with water or other liquid, I may provide any suitable means, but I have illustrated a water container or reservoir 25, from which a tube 26 leads, which tube is preferably of copper and discharges into one end of the reservoir. This reservoir is mounted in a suitable support 27 above the end of the tank so that the water in the tank is kept at a constant level 90 sufficient so that the rollers 15 will be partially submerged. 95

I have heretofore alluded to the fact that the shaft 14 is mounted in suitable bearings. Preferably these bearings will be in the 100 form of arms 28 pivoted upon brackets 29 projecting from the rear wall of the tank so that the shaft 14 and its rollers 15 may be lifted bodily out of the tank to permit the tank to be cleaned and to permit the rollers to be cleaned. Preferably one end of the tank is provided with a drainage cock 30 whereby the tank may be drained. Preferably also the shaft 14 will be in sections, as illustrated in Figure 1, where I have 105 shown a short section x, a section y, and a section z. These sections are joined, as illustrated, by forming one of the sections, as for instance the section y, with a tongue 31 extending into a recess in the end of the next adjacent section, this recess extending to the surface of the shaft so that one section may be lifted out without lifting out 110 the other section of the shaft. 115

If the yarn extended at a true tangent to the surface or periphery of the roller 15, it would only touch this roller at one point and its shaft with the roller would be relatively small so that it would take up only a 120 relatively small amount of moisture from the roller. In order to cause the yarn to take up a greater amount of moisture, it is necessary to provide means whereby the yarn may be forced into contact with the periphery of the roller over a relatively considerable surface. To this end I mount upon one wall of the tank and in association with each roller 15 a finger 32 which has its upper and under faces extending approximately parallel to the upper edge of 125 130

the wall and therefore approximately parallel to the longitudinal axis of the shaft 14, this finger being angularly extended at one end, as at 33, for attachment to the wall and 5 the opposite end of the finger being upwardly and outwardly beveled, as at 34. At the junction of the angular bevel 34 with the inner face 35 of this finger there is formed a lip 36 which constitutes a stop and the 10 yarn normally slides back and forth between the lip or stop 36 and the inner edge of the angular end 33 of the finger. When the yarn is first placed upon the machine or in case of splicing of the yarn, the yarn extends over the upper edge of the finger, but 15 as the yarn travels toward the right in Figure 6, it reaches the end of the finger and on its return the beveled edge 34 catches the yarn and guides it downward until it 20 passes the stop 36 and is beneath the finger and travels along the edge 35. This edge is rounded so as not to abrade the yarn. When the yarn travels under the edge 35 it is caused to conform to the surface of the 25 roller 15 for a certain distance so that it will come in full contact with the roller. Thus as the roller 15 is given a step by step rotation, it will carry water upward and bring it in contact with the yarn so 30 that the twist of the yarn becomes set.

As before stated, the face of the roller is preferably formed with longitudinally extending recesses forming buckets, as they might be termed, which act to lift a certain 35 amount of water up on the roller and carry the water around so that the yarn is fully moistened. It will be obvious that by decreasing the speed of the roller a less amount of water will be carried to the yarn and that 40 by increasing the speed of the roller 15 a greater amount of water will be carried to the yarn. It will further be obvious that if the finger 32 be vertically adjustable, as by the screws 37, the amount of contact between the yarn and the face of the roller 45 will be controlled.

Because of the conical shape of the tapered cone on which the yarn is received, the speed of the yarn traveling over the 50 roller 15 varies, depending upon its point of contact with the winding cone B. Thus if the yarn is being wound upon the small portion of the cone it will have a lower speed than if it is being wound upon the 55 large portion of the cone. Now if the rollers 15 were uniform in diameter, they would give the same amount of water to the thread whether the thread were moving at a relatively rapid speed or at a relatively slow speed. Thus portions of the thread would 60 secure more water than other portions. I therefore form these rollers 15 conical or in the form of a frustum of a cone so that when the yarn is being wound over the small 65 portion of the cone B it will be passing over

the small portion of the conical roller 15, and when the yarn is being wound around the large portion of the cone B the yarn will be passing over the large portion of the roller and will receive more water. In other 70 words, it will come in contact with the roller for a greater length of time or for a greater distance than when the yarn is passing over the small portion of the cone.

While I have heretofore referred to this 75 mechanism as being used primarily for the purpose of moistening the yarn or thread so as to prevent the yarn or thread from kinking and for the purpose of setting the twist, I do not wish to be limited to this use inasmuch as the device may be also used for 80 dyeing the yarn. Thus, for instance, if it be desired to produce a gray yarn the tank is filled with a black dye and this black dye applied by the rollers to the white yarn 85 causes the yarn to have a gray effect. I have used black dye as an illustration, but it will be understood that the dye might be red, blue, or any other color, but the resulting yarn would have a tint 90 formed by applying the colored dye to a white yarn. Heretofore in forming a gray yarn it has been necessary to take a certain amount of black cotton and a certain amount of white cotton and mix them 95 so as to form a gray yarn. By this device, however, it is an easy matter to control the tone of the yarn and secure these colored yarns as they are being wound upon the 100 winding cone.

I do not wish to be limited to a step by 105 stey mechanism for the purpose of rotating the shaft 14 and rollers 15, as means may be provided where by the rollers may be given a continuous rotation, but I have found in practice that a step by step mechanism of the character described is much less expensive to install and yet is thoroughly effective for the purpose, as the stop motion shaft previously described affords means 110 whereby a step by step motion may be readily operated. My mechanism does away with the conditioning room and eliminates the necessity of leaving the cones in the conditioning room for some twenty-four hours in order 115 to secure the proper degree of moisture in the yarn. Furthermore, the yarn is more uniformly moistened and all danger of over-wetting the surface of the wound cone of yarn is eliminated, thus preventing the yarn 120 from mildewing. Further, my means permits oil to be applied to the yarn, if desired, either with or without water, and permits the application of dyes thereto. It will be noted that the dyes will act to moisten the 125 yarn in the same way as water does so that the yarn is conditioned and dyed at the same time.

My object in providing a relatively long 130 shaft with separated rollers 15 for each yarn

or thread is by that means I reduce the weight of the shaft 14, which would have to be relatively heavy did it constitute one long roller extending the full length of the machine. These rollers 15 dip directly into the water in the tank. I have found in practice that if a dry roller is used whereby water is carried from the tank and then applied to the roller 15, the roller 15 does not receive sufficient water and moisten the thread properly. It will be obvious that by changing the speed of the shaft 14 that various percentages of the water may be readily applied to the yarn and that the same result might be secured by adjusting the finger 32 to cause the yarn to contact with the roller 15 to a greater or less extent. Once the thread has passed beneath the finger 32, it will be guided back and forth beneath the finger and held from passing off the finger by the angular end 33 and by the stop 36.

I do not wish to be limited to the exact form of mechanism illustrated, as it is obvious that these might be changed in many ways without departing from the spirit of the invention.

I claim:

1. In a yarn treating tank, a roller mounted therein, the tank being adapted to hold water and the roller being partially submerged in the tank, means for guiding yarn over and in contact with the roller, and means for rotating the roller, the roller being formed with a series of longitudinally extending liquid holding recesses, each of these recesses having a radially extending wall and a wall inclined from the inner end of the radial wall of the outer face of the roller and in the direction of rotation of the roller.

2. A yarn treating mechanism including an elongated tank, a shaft passing through the tank, a series of rollers spaced from each other and mounted upon the shaft and projecting above the tank, the tank being adapted to hold liquid, the rollers dipping into said liquid, a series of brackets pivoted upon the tank and supporting said shaft whereby the shaft and rollers may be lifted out of the tank, and means for causing the yarn to travel over the faces of and against the rollers.

3. In a winding machine having a series of quills and a series of winding cones associated with the quills, the winding cones taking yarn from the quills, said machine having an oscillating arm, a tank disposed longitudinally between the quills and the winding cones and in the path of movement of the yarn passing from the quills to the cones, said tank being adapted to contain liquid, a shaft extending longitudinally through the tank, a series of rollers mounted upon the shaft dipping into the liquid

in the tank, means for causing the yarn to pass over a portion of the periphery of each roller to thereby take up the liquid on the roller, means for giving a step by step rotation to said shaft comprising a ratchet wheel thereon, an arm pivoted concentrically to the axis of the ratchet wheel, a pawl carried by the arm, the last named arm having a series of holes, and a pin adjustable in any one of said holes with which the first named arm is adapted to engage.

4. In a cotton yarn winding machine having a quill from which the yarn is adapted to be discharged, and a winding cone upon which the yarn is received, a moistening roller disposed between the quill and the winding cone, the roller being tapered to correspond to the taper of the cone.

5. In a cotton-yarn winding machine having a quill from which the yarn is adapted to be discharged, and a winding cone upon which the yarn is received, a tank adapted to contain liquid and disposed between the quill and the winding cone, and a roller disposed within the tank and projecting above the same and dipping into the liquid therein, with the periphery of which said yarn contacts, the roller being tapered in approximate conformity to the taper of the cone.

6. In a cotton yarn winding machine having a quill from which the yarn is discharged and a winding cone upon which the yarn is received, and means associated with the cone for causing the yarn to travel back and forth upon the cone, means for moistening the yarn comprising a tank disposed between the quill and the cone, and a roller disposed within the tank and dipping into the liquid thereof and with the periphery of which the yarn contacts, the roller being tapered to conform to the taper of the cone.

7. A yarn treating mechanism including an elongated tank, a shaft extending longitudinally through the tank and formed with a series of sections, the sections having detachable rotative engagement with each other, means supporting each section for rotative movement within the tank but permitting the removal from the tank of each section independently of any other section, and a series of rollers spaced from each other and mounted upon the shaft sections, the tank being adapted to hold liquid and the rollers dipping into said liquid, and means for causing a series of yarn threads to pass over said rollers and come in contact therewith.

8. A yarn treating mechanism including an elongated tank, a shaft passing through the tank, a series of rollers spaced from each other and mounted upon the shaft, the tank being adapted to hold liquid, the rollers dipping into said liquid, means for causing a series of yarn threads to pass over said rollers and come in contact therewith, the

shaft being formed in sections and each section having at one end a diametrically extending groove and at the other end a tongue adapted to fit into said groove where-
5 by the sections have detachable rotative en-
gagement, and means for rotatively sup-
porting each of said sections within the

tank, said means permitting the lifting of any of the sections from the tank inde-
pendently of any other section. 10

In testimony whereof I hereunto affix my
signature.

JAMES A. JOHNSON.
